(57) **CLAIM**

The ornamental design for a stand on sulky, as shown and described.

DESCRIPTION

FIG. 1 is a perspective view taken generally from the top of a stand on sulky showing my new design;

FIG. 2 is a perspective view taken generally from the bottom thereof;

FIG. 3 is a perspective view taken generally from the back thereof;

FIG. 4 is an elevational view from the back side thereof;

FIG. 5 is an elevational view from the front side thereof;

FIG. 6 is an elevational view taken from the left side thereof;

FIG. 7 is an elevational view taken from the right side thereof;

FIG. 8 is a top plan view thereof;

FIG. 9 is a bottom plan view thereof;

FIG. 10 is a perspective view taken general from the top and showing the foot supports in a depressed configuration thereof;

FIG. 11 is a perspective view taken generally from the bottom and showing the foot supports in a depressed configuration thereof;

FIG. 12 is a perspective view taken generally from the back thereof and showing the foot supports in a depressed configuration thereof; and,

FIG. 13 is an elevational view taken from the left side and showing the foot supports in a depressed configuration.
